[57] ABSTRACT

In a hydrodealkylation process the vent hydrogen stream from the reaction zone is contacted with 5 to 20 mole percent of liquid C₇ to C₉ aromatics in one or two stages. The mixture is then flashed to yield a liquid containing about 95 percent of the benzene entering the flashing zone.

PURIFICATION OF HYDRODEALKYLATION REACTION
VENT HYDROGEN

BACKGROUND

An important consideration in a flowsheet for the hydrodealkylation of alkylated aromatic hydrocarbons is the handling of the vent hydrogen vapor. This vapor contains a substantial amount of benzene. The exact amount is a function of the amount of net effluent gas as well as the temperatures and pressure of the effluent flash drum. However, the benzene in this effluent can be in the range from 2-10 percent of the total benzene production. It is, therefore, essential to the efficiency of the overall process that this benzene be recovered.

Although the prior art which used many contacting stages, of which U.S. Pat. No. 3,287,431 is an example, has been able to recover this benzene, it now is proposed to obtain the same results more economically by using fewer stages.

The aromatics content in the vent hydrogen is about 1 to 1½ volume percent and is comprised mainly of benzene and toluene in ratios between 5:1 to 20:1. When the ratio of toluene to benzene in the vent hydrogen is greater than 8:1 then the danger of freezing at purification temperatures of as low as -200° F is removed.

In the prior art, the method of recovering aromatics and also to reverse the benzene to toluene ratio has been to use a vent hydrogen absorber. In the absorber, a small amount of toluene and heavier aromatics are used to scrub the vent gas in multi-tray towers. While this method is effective, it is an expensive method.

SUMMARY

Instead of an absorber for reversing the benzene to toluene ratios and recovering the benzene, it is still possible to take advantage of the large differences in the equilibrium constants (K values) by using a larger quantity of contacting liquid with only one or two stages.

In the operation of hydrodealkylation unit to make benzene or naphthalene, the net reactor effluent is flashed in a flash drum at a temperature between about 100° to 150° F and at a pressure between about 500 to 600 psig to produce a vapor and liquid stream. The purpose of this flash is twofold.

It first provides a liquid stream comprised mainly of product aromatics such as benzene or naphthalene and unconverted aromatic feed. The liquid stream has dissolved in it a small amount of light gases and saturated hydrocarbons resulting from the hydrodealkylation reactions, such as hydrogen, methane, ethane, propane, hydrogen sulfide, thiophene, etc. Some of these are removed in the stabilizer; and subsequent fractionation results in pure product.

Secondly, a vapor stream containing about 55 percent hydrogen is formed. In the vapor, the aromatics content is about 1 to 1½ volume percent and is comprised mainly of benzene and toluene in a range from 5:1 to 20:1. It is undesirable to vent these aromatics because this represents an economic waste of valuable product and feed. The high benzene to toluene ratio is also detrimental if a hydrogen purification unit is used to upgrade the purity of the vent gas.

In order to take advantage of the differences in equilibrium constants by flashing, an amount of liquid toluene or heavier aromatics equal to about 5 to 20 mol percent of the vent gas is intimately admixed with the vapor stream. The resulting vapor-liquid equilibrium mixture is cooled below ambient conditions by refrigeration and then separated in a drum. The net result is that at least 95 percent of the benzene gets into the liquid phase and only a small amount of toluene is vaporized. Another method of achieving these results is to inject the liquid aromatics in two consecutive portions, which may not be of equal amounts, while also using refrigeration, as above, to perform the flashes at a somewhat lower temperature than ambient in order to decrease the K value of benzene.

Single stage mixing is used when a toluene to benzene ratio of less than 8:1 is sufficient. In this case the vent hydrogen is not sent to a hydrogen purification unit.

Two stage mixing is used when a toluene to benzene ratio of greater than 8:1 is required. In this case the vent hydrogen is sent to a hydrogen purification unit.

An object of this invention is to minimize the loss of total aromatics in the vent hydrogen stream.

Another object of this invention is to control the ratio of toluene to benzene in the vent hydrogen stream without using an absorber.

Further objects of this invention will become apparent from the following description of the preferred embodiment thereof and as more particularly shown in the attached drawing.

DESCRIPTION OF THE DRAWING

15 The drawing is a schematic flow diagram of a hydrodealkylation process wherein the vent hydrogen stream enters a liquid vapor equilibrium staging process for purification.

DETAILED DESCRIPTION OF THE DRAWING

20 Hydrogen is passed in line 12 and through compressor 18 to line 30 prior to combining with the feed. The alkylated aromatic hydrocarbon feed passes in line 10 and part of this feed mixes with hydrogen feed in line 39 via line 14.

25 Toluene or mixed alkylated aromatic hydrocarbons are suitable as feed material. Toluene is the most preferred feed while mixed alkylated aromatics containing considerable toluene is less preferred and mixed alkylated aromatics containing no toluene is least preferred. The above feeds, in order to be suitable, must contain less than about 1 percent benzene but may contain some saturated non-aromatics. Diolefins and olefins contained in the feed must be removed to make a feed suitable for use in the hydrodealkylation system and it is desirable to minimize the thiophenic sulfur in the feed stream. Such treatment steps are not shown in this system as the most preferred feed is a toluene feed.

30 The combined hydrogen and feed in line 39 is mixed with recycle hydrogen in line 83 and rich oil in 28 and is heated at 40 by exchange against reactor effluent. At this point a stream 40 from the stabilizer 60 is added and the total reactor feed is heated to about 1,200° F in fired heater 42. It then enters the reactor 44.

35 The reactor 44 is an internally insulated open chamber containing no catalytic surfaces. The pressure in this reactor is maintained at about 600 psig. The reactor is so sized that the residence time of the total feed is in the range of about 20 to 40 seconds. The temperature profile in the reactor is controlled by adding quench gas at appropriate points in the reactor such as 52. The temperature profile is so controlled that it does not exceed 1,350° F at any point within the reactor. It is also controlled so that about 75 percent of the alkylated aromatic hydrocarbons in the total feed is converted. At the outlet 55 the reactor effluent is quenched to about 1,200° F by liquid quench 56. While quenching in this manner is sufficient to stop the reactions which occur in the reactor 44, it does permit reactions to take place which produce certain hydrocarbon impurities which form azeotropic boiling mixtures with benzene.

40 The reactor effluent 46 is then cooled by exchange against reactor feed at 40, by exchange against stabilizer feed at 47, and by water at 48. It is then separated into liquid and vapor in flash chamber 50. Part of the flashed vapor in 51 is passed through compressor 20 and is used to quench the reactor at 52 and also to supply recycle hydrogen for control of the hydrogen to aromatics ratio at the inlet to the reactor via line 83. The net vapor is taken at 53 and cooled to about 80° F in exchanger 54 by exchange against the liquid in 28 from the two stage flash drum 34 and the vapor from 34 in line 35. If the hydrogen in line 35 is to be passed to a hydrogen purification unit it would not pass through heat exchanger 54 but it would go directly to the hydrogen purification unit.

45 The cooled vent hydrogen stream in 57 combines with the feed from line 19 or recycle aromatics in 37 before undergoing further cooling to about 65° F in 22. The cooled mixture

now passes in 25 to the first stage of 34 where it undergoes a flashing to produce a liquid stream containing about 10 to 20 percent benzene in 31 and a vapor stream which contains 0.2 to 0.6 percent aromatics in 21 with a toluene to benzene ratio of about 2 to 1.

The vapor in 21 combines with feed from 16 or recycle aromatics in 84 to pass through line 23 to the second flashing stage at 34. In the second stage, there is a flashing of the mixture to provide a liquid stream in 27 which combines with the first stage liquid to leave in 31. The vapor effluent from the second stage of 34 in 35 contains about 0.2 to 0.5 percent aromatics with a toluene to benzene ratio of about 11 to 1.

Part of the liquid from flash chamber 50 is taken through line 56 and used to quench the reactor effluent at 55. The net liquid from 50 passes through and is reduced in pressure through valve 59 and is heated at 47 by exchange against reactor effluent and then goes by 58 to the stabilizer 60. If recycle aromatics in 37 and 84 are used as the contacting liquids and an additional quantity of this material is required, then the net liquid at 50, after reduction in pressure, is combined with rich oil in 32.

Light hydrocarbon gases which are present in the stabilizer feed 58 are taken overhead of the stabilizer 60 at 62. In addition, a small sidestream is taken at 65, a few trays from the top, and returned to the reactor 44. This sidestream is primarily benzene, but contains hydrocarbons impurities, formed most probably after the reactor quench, which form azeotropic boiling mixtures with benzene. If these impurities were allowed to remain in the benzene product, its premium quality would be lost. Alternatively, if the azeotropic mixtures were removed, expensive high efficiency fractionation would be required and the yield of premium quality benzene would be reduced. By returning these azeotropic mixtures of benzene and hydrocarbon impurities to reactor 44 the impurities are destroyed by hydrocracking and the high yields of premium quality benzene are produced.

The bottoms from the stabilizer 60 are taken at 66 as feed to the clay tower 68. The operating pressure of the stabilizer 60 is maintained at that necessary to give a bottoms temperature of about 425° F. This enables the bottoms 66 to go directly to the clay tower without intermediate heating. The stabilizer is furnished with a reboiler 64.

The clay tower effluent 69 goes directly to the benzene tower 70. This is a conventional fractionator operating at essentially atmospheric pressure and reboiled at 76. High purity benzene product is taken as the overhead product at 72. With feeds other than toluene the bottoms 74 are preferably sent by line 77 to the recycle tower at 78. For toluene feed, the bottoms containing the recycle aromatics are sent directly back to the reactor through line 75.

The recycle tower 78 is run at atmospheric pressure. The overhead 79 is essentially rich in alkylated aromatics primarily toluene with recycle diphenyl and water vapor. The overhead in 79 passes through condenser 81 and separator 85 with the water removed in 86. A portion of the toluene and recycle diphenyl is returned to 78 and the remainder is sent through line 80 to be used as recycle for the system.

In the event that it is necessary to use the recycle aromatics as a contacting liquid, then the following procedure can be followed. The unconverted toluene, the quantity of which depends on per pass conversion, can be returned to the reactor 44 through line 37 and 84. The selection of bypasses 37 and 84 is dictated by the requirements in 34. If extra lean oil is desired in 34, bypasses 37 and 84 are used and all of line 80 is chilled and used as contacting liquid. If the demand in 34 is low, the unconverted toluene can be sent directly to the reac-

tor via line 39 and in so doing, bypass 34. The rich oil in 31 is sent to the reactor in 28. If the lean oil bypass system is utilized to create additional aromatic recycle, then the excess rich oil in 32 is combined with the net liquid from the reactor effluent flash drum 50 and is sent directly to the stabilizer 60 and then to the benzene tower 70 and recycle tower 78 for removal of the light components and benzene that were recovered in 34.

It will be understood that the foregoing description and disclosure does not include all of the customary valves, controls and interconduit heat exchangers, but it will be appreciated that temperatures are readily controlled and heat recovered in the well-known manner.

Generally, hydrodealkylation operations are conducted in the temperature range of 1,000° to 1,500° F and temperature differences can be kept at 200° F or less. The operating pressures are normally in the range of 400 to 800 psig with a reaction time within the period of 10 to 60 seconds. There will be at least 2 moles of hydrogen per mole of liquid aromatic feed.

We claim:

1. A process for the hydrodealkylation of alkylated aromatic hydrocarbon feed which comprises the steps of:
  - a. passing the feed and hydrogen to a reaction zone;
  - b. operating the reaction zone between about 1,000° F and about 1,500° F and a pressure between about 400 psig and about 800 psig;
  - c. removing a gas-liquid effluent stream from the reaction zone;
  - d. cooling said effluent;
  - e. feeding said effluent to a first separation zone where a hydrogen-rich vapor is separated from the liquid containing portion of the effluent, the treatment of which will hereinafter be described;
  - f. passing the liquid effluent to a second separation zone to obtain a light hydrocarbon gaseous effluent and a liquid bottoms;
  - g. passing the liquid bottoms to a third separation zone to obtain a benzene effluent and a liquid bottoms;
  - h. contacting the hydrogen from step (e) with heavy hydrocarbons to shift the benzene-toluene equilibrium;
  - i. feeding the hydrogen and heavy hydrocarbons mixture to a flashing zone;
  - j. flashing the mixture to obtain a liquid phase of 5 to 15 percent benzene and a vapor phase of 0.2 to 0.5 percent aromatics with a toluene to benzene ratio from 2 to 1 to 15 to 1;
  - k. recovering the benzene as product from step (j).
2. The process of claim 1 wherein a sidestream of benzene and azeotropic forming hydrocarbon impurities is removed from the second separation zone in step (f) and recycled to the reaction zone in step (a).
3. The process in claim 1 wherein the liquid bottoms from the third separation zone is passed to a fourth separation zone for removal of the heavy aromatics as a bottoms and the overhead from this separation zone is recycled for use as the heavy hydrocarbons in step (h).
4. The process of claim 1 wherein the feed is used as the heavy hydrocarbon in step (h).
5. The process of claim 1 wherein the hydrogen in step (j) has a toluene to benzene ratio of less than 8 to 1.
6. The process of claim 5 wherein the hydrogen from step (j) has a toluene to benzene ratio of greater than 8 to 1 and is fed to a hydrogen purification unit.
7. The process of claim 1 wherein the liquid bottoms from the third separation zone is recycled for use as the heavy hydrocarbons in step (h).
